UNITED STATES PATENT OFFICE.

JOHN H. BARNARD, OF BROOKLYN, NEW YORK, ASSIGNOR TO AMERICAN LOCOMOTIVE COMPANY, OF NEW YORK, N. Y., A CORPORATION OF NEW YORK.

INTERNAL-COMBUSTION-ENGINE LOCOMOTIVE.

Application filed January 31, 1921. Serial No. 441,802.

To all whom it may concern:

Be it known that I, JOHN H. BARNARD, a citizen of the United States, and resident of Brooklyn, in the county of Kings and 5 State of New York, have invented a certain new and useful Improvement in Internal-Combustion-Engine Locomotives, of which improvement the following is a specification.

10 This invention relates to the application of internal combustion engines to the propulsion of locomotives and to the driving of any apparatus of similar load characteristics, wherein it is required that substantially the whole load shall be started from 15 a state of rest, and without the interposition of slipping clutches or other devices, for permitting the power to be gradually applied to the load.

20 My invention therefore contemplates an apparatus of this character in which the pistons of the internal combustion engines are provided with positive driving connections with an axle or axles of the locomotive, or with a power shaft carrying the load, and one of the features of my improvement comprises additional means for originating motion and assisting the piston effort in starting and in accelerating to a 25 fair rate of speed for the engine.

As is well known in the practice of steam locomotion, it has been found that the use of a pair of double acting steam cylinders located in substantially a horizontal plane, and having pistons provided with cross heads and connecting rods for directly operating two or more coupled driving axles, has given the best results in providing the desired flexibility and for accommodating 35 the variations caused by irregularities in the surface of the track.

Another object of my invention is, therefore, to provide an internal combustion engine traction unit approximating as nearly 45 as possible to this prior standard steam locomotive design as regards the arrangement of cylinders and pistons and their connections to the axles to give a similar driving effect. For this purpose, I propose to use 50 single acting combustion cylinders of the

two-stroke type, thus requiring double the number of cylinders in order to produce the desired piston effort or number of impulses per revolution of the axle, and in order to provide for road clearance, flexibility and 55 compactness, I preferably locate two pairs of opposed cylinders between the driving wheels and connect the pistons of one pair to a pair of staggered cranks on one driving axle, and the pistons of the opposing 60 cylinders to a pair of staggered cranks on the adjacent axle. The cylinders may be slightly inclined to the horizontal in order to prevent interference between the connecting rods of one axle and the cranks of the 65 adjacent axle.

By this system of grouping, I obtain the advantage of steam locomotive design and produce an internal combustion engine traction unit of minimum length having two 70 pairs of opposed cylinders of maximum diameter for two pairs of driving wheels located at a comparatively short distance, center to center. The side frames and axle journals may be placed outside the driving 75 wheels and the axles coupled by side rods on cranks outside of the journal boxes. The axles, with their cranks, are thus maintained at the desired relation of lag or lead with respect to each other and the pair are equivalent to a single axle of four throws, and having the same number of impulses, as in a steam locomotive. If a single traction unit be sufficient for the power desired, the side frames may be extended for a pair of 80 trail wheels at one end, and a swivelled pilot truck at the other for a complete locomotive, or if it be desired to employ two or more traction units, the frames may be adapted to couple said units together either with or 85 without trail wheels. Where two traction units are employed for a locomotive, the two sets of driving axles are coupled together by a suitable mechanical connection to maintain the desired phase relation between the 90 power units, and this comprises another feature of my invention.

According to another feature of my improvement, the pistons of the engine cylinders are double acting, each having a piston 100

rod extending through the inner head of the cylinder and connected to a sliding cross head attached to the connecting rod, and the inner end of the cylinder at the side of the piston opposite the combustion end is used for operating the engine by a compressed fluid, such as air, introduced through suitable valve devices, for assisting in the starting and the acceleration of the engine. By this means, each cylinder not only acts as an internal combustion engine, but also as a single acting compressed air motor during the return stroke, and the compressed air also serves to abstract some of the excessive heat from the cylinder walls, which heat further increases the expansive force of the air.

In order to provide a storage of compressed air for use in the engine cylinder, air compressing means may be operated by the engine, or by a non-driving axle of the locomotive, or by other means, and I also preferably heat said compressed air by the exhaust gases from the internal combustion engine.

Another object of my invention is to reduce to a minimum, the period of slow piston travel in starting and accelerating, for which purpose I propose to employ dynamo-electric machines adapted to be driven by other or non-driving wheels, and to serve as generators to charge a storage battery during the periods of running down grade, and for retarding or decelerating the train, and then, during acceleration or peak duty, utilizing the energy thus stored to actuate said dynamo-electric machines as motors to assist in driving the engine. Further, I may use this stored electric power to drive a second stage compressor, or I may use trailer truck wheels to drive this second stage compressor during periods of retardation or light duty, for compressing air to higher pressures for storage in smaller space. Then, during times when the working air receivers are not being replenished, the high pressure air may be used for this purpose, through a reducing valve, if desired, and this compressed air may also be heated by the exhaust gases from the engine.

In the accompanying drawings: Figure 1 is a vertical longitudinal section, taken substantially on the line 1—1 of Fig. 2, and showing, in diagram, an internal combustion engine embodying my improvement; Fig. 2, a plan of the same, with the upper elements removed to show more clearly the arrangement of cylinders and cranks; Fig. 3, a plan, showing the truck frames and axles of two traction units coupled together, with the cranks in the desired relation; Fig. 4, a vertical longitudinal section taken on the line 4—4 of Fig. 3; Fig. 5, a diagram, showing two pairs of cylinders inclined at any requisite angle, with a hori-

zontal plane through the axles of the two pairs of driving wheels, and indicating the proper lag or lead of the cranks of one axle with respect to those of the other; Fig. 6, an enlarged detail, in vertical longitudinal section, taken on the line 6—6 of Fig. 7, of a flexible connection between the end sills of the abutting frames of two traction units; Fig. 7, a plan of the same; Fig. 8, an end elevation of one of the end frames; and, Fig. 9, a horizontal section of the adjoining ends of two frames with a flexible connection between them.

To avoid unnecessarily encumbering the drawings, there are omitted many well known parts and details which form no part of my present invention, such as fuel supply, timed valve mechanism for the combustion and the air ends of the engine cylinders, ignition devices, electric and other controls, radiators for cooling circulating water, etc., all of which parts are well understood by those familiar with the art, and there are included only such features as are deemed necessary to a clear understanding of the invention and its operation.

According to the construction shown in Figs. 1 and 2, my improved internal combustion engine traction unit comprises two pairs of driving wheels mounted on the respective axles, 11 and 12, each having a pair of inside cranks, 11^a, 11^a, and 12^a, 12^a, respectively, the cranks of each axle being preferably arranged 180 degrees apart, and the cranks of the respective axles being staggered with reference to each other. The side frames, 13, supported on the journal boxes, 14, mounted on the driving axles, are preferably located outside of the driving wheels, while outside of the frames the axles are provided with cranks, 11^b and 12^b, connected by the two side or parallel rods, 15. Supported on transverse saddles, 16, carried by the side frames, 13, are two opposed pairs of cylinders, 17, 17, and 18, 18, the cylinders of the respective pairs being staggered to correspond with the inside cranks of the axles, and each cylinder being fitted with a piston, 19, having a rod, 20, extending through a gland in the inner head of the cylinder and attached to a cross head, 21, mounted to slide in guides, 22, and connected with one of the opposite cranks by a connecting rod, 23. The connecting rods of cylinders, 17, 17, are coupled to cranks, 11^a, 11^a, of one axle, 11, while the connecting rods of cylinders, 18, 18, are coupled to cranks, 12^a, 12^a, of the other driving axle, 12.

The two opposing pairs of cylinders may be inclined upwardly in opposite directions, and the side rods coupling the outside cranks maintain the proper phase relations between the two axles. This will more fully appear by reference to the diagram, Fig. 5, in which

I have shown the two opposing cylinders, 17 and 18, inclined at the angle, x , with the horizontal plane through the centers of the axles, 11 and 12, and with their axes intersecting at a point, I, forming, with each other, the angle, y . If it be desired that the crank throws of each axle shall be 180 degrees apart, and that those of one axle shall be on center when those of the other are 90 degrees from centers, then the crank pin, 11^a, will be in the line 17—11, when the crank arm, 12^a, is at right angles with the line 18—12, and the difference between the crank angles is the angle formed by the extension of the line 12—12^a, with the line 17—11, which will be seen to equal $90 - 2x$. However, it will also be seen that $2x = 180 - y$, hence by substitution, the desired angle equals $90 - (180 - y)$ or $y - 90$. If the angle of inclination of the axes of the cylinders to the horizontal be, say 24 degrees, the angle at the intersection of the axes will be 132 degrees, and the angle of the crank 12^a, will be 66 degrees when the crank, 11^a, is on center. In either case, the angular position of the side rod cranks of each axle would be formed 90 degrees apart, and their position with respect to the driving cranks would form part of the determination of the counterbalancing.

It will be understood that any suitable or preferred form of internal combustion engine may be employed having suitable timing valve mechanism and ignition, which parts, however, are not shown in the drawings, as they are well known to those skilled in the art. The outer end of the cylinder at the outer face of the piston serves as the combustion end of the cylinder, while the other end of the cylinder at the opposite face of the piston operates as the compressed air motor end for assisting the engine in starting, and during heavy duty. Any suitable means may be employed for compressing the air for this purpose, but I have shown a preferred construction comprising air compressing cylinders, 25, mounted axially upon the outer head of the combustion cylinders, and each having a piston, 26, and tail rod, 27, extending through a packing gland, in the combustion head and connected to the main piston rod, 20. In this way the air compressor may be driven by the rotation of the driving axles when running down grade, or by the engine whenever desired, as when working under light duty, and operate to compress air through pipes, 28, into suitable receivers or storage tanks, 29, from which it flows through the heater, 30, and pipes, 31, to the inner ends of the power cylinders in order to operate the same as compressed air motors at such times as may be desired. The suction and discharge valves, unloading devices, etc., for the air compressors, as well as the con-

trolling valve mechanism for the air motors, are not shown in the drawings, as those skilled in the art are familiar with such well known mechanisms, and can readily apply the same for use in this connection. The exhaust gases from the engine pass through discharge pipes, 32, into the heaters, 30 and 30^a, thence through the tubes of said heaters, and out at the exhaust stack, 33.

For the purpose of storing compressed air at a higher pressure, if desired, I have shown a second stage compressor, 35, driven by the axle, 36, of a pair of trailing wheels, the intake of the pump being connected to pipe, 28, and the receivers, 29, while the discharge communicates by a pipe, 37, with high pressure storage tanks or receivers, 38. The compressor, 35, may be provided with the usual valves, unloading devices and controlling means (not shown), whereby it may be thrown into operation during light duty, as when descending grades and decelerating, and cut out of operation at other times.

In starting the locomotive, and at such other times of heavy duty, as may be desired, compressed air is drawn from the low pressure receivers, 29, through the heater, 30, pipes, 31, and suitable valve means to the inner or air motor end of the engine cylinders, where it exerts its pressure upon the inner faces of the pistons during the outward or scavenging strokes at each revolution. If a suitable degree of pressure be maintained in the receivers, 29, the locomotive can be started and a sufficient piston speed developed by the action of the compressed air before the ignition is started in the combustion end of the cylinders. The air motor may then be cut out of effective action, or may be continued to assist the engine during the operation of the combustion of gases at the other end of the cylinders, as desired.

If the demand upon the low pressure receivers, 29, is greater than can be supplied by the compressors, 25, or when it is desired to concentrate the effort of the power cylinders, air from the high pressure receivers, 38, may be allowed to flow through a reducing valve, indicated at 40, to reinforce the supply of the receivers, 29. This supplemental supply from the high pressure receivers is also preferably passed through one of the heaters, 30^a, where it is warmed by the exhaust gases from the engine.

The side frames, 13, may be extended at the front for a pilot truck having axles, 42, and swivelled at 41 to the frame. In order to utilize these pilot wheels for traction purposes, I provide electric generators, 43, geared to said axles in the usual manner and connected up by suitable leads with a storage battery, 44. The generators are also adapted to be operated as motors by current from the storage battery. Suitable well

known electric control and switch devices, (not shown), may be employed for connecting the electric machines to operate either as generators driven by the momentum of the locomotive, as when descending grades, or as motors for assisting the tractive effort of the locomotive in starting and during peak duty.

Where two or more tractive units are assembled together for one locomotive, I prefer to have the frames for the same flexibly coupled together, and for this purpose, I have shown, in Figs. 3 to 8, a forged box end frame having curved end sills, 45, joining the side frames, 13, and provided with elongated slots, 46, at the box portion. The curved end frames of two units are then coupled together by a coupling, such as shown in Figs. 6 and 7, comprising two link members extending through the slots, 46, in the two abutting end frames, 45, one member having a head, 47, shank, 48, and block, 49, carrying rollers, 50, secured at the end of the shank by adjustable nuts, 51, and the other member formed with a socket portion, 47^a, having shank, 48^a, with a similar block, 49, rollers, 50, and nuts, 51. The head, 47, fits within the socket, 47^a, with the capacity of relative vertical movement, these parts being located between the abutting curved end frames, 45, while the rollers, 50, are adapted to bear upon the inside of the curved end frames. As the traction units swing relative to each other in passing around a curved portion of the track, the coupling is adapted to roll upon the curved end frames and hold the units together with the desired amount of flexibility. The socket portion, 47^a, may also be provided with rollers to engage the outer face of the curved end frames and thereby eliminate slack when the nuts are properly adjusted.

Referring to Figs 3 and 4, there is shown means for keeping the axles of one traction unit in any predetermined phase relation with those of the adjacent unit, and while various forms of mechanical connections may be employed for this purpose, I have shown, on each unit, a bevel gear, 52, mounted on the axle, 12, meshing with bevel pinion, 53, mounted in a suitable bearing, and driving a shaft, 55, through a universal joint, 54, the rods or shafts, 55, 55, being joined at the coupling by a sliding sleeve, 56, to form a slip joint. In a multi-traction unit locomotive, it will, of course, be desirable that there be an even distribution of the firing intervals in order to afford regularity of draw bar pull, and an even distribution of duty upon the several pistons of the internal combustion cylinders. It will be apparent that this advantage will be obtained in my improved construction having a positive mechanical connection between the axles of the adjoining units, and the uniform timing of the firing interval will be ob-

tained by the proper adjustment of the respective side rod cranks upon the axles in accordance with the number of axles and the type of internal combustion employed, as will be readily understood.

Having now described my invention, what I claim as new and desire to secure by Letters Patent is:

1. In an internal combustion engine locomotive, the combination of a double ended engine cylinder and piston having a combustion space at one side of the piston, and a fluid pressure space at the other side, a piston rod extending through the end of the cylinder, a positive driving connection from said rod to a driving axle, an air compressing cylinder mounted axially on the combustion head of the engine cylinder, a piston in the compressor cylinder having a rod connected to the engine piston, and means for supplying said compressed air to the fluid pressure side of the engine piston to assist in starting the locomotive.

2. In an internal combustion engine locomotive, the combination of an internal combustion engine cylinder and piston having a positive driving connection with the driving wheels, air compressing mechanism operated during the running of the locomotive, means for heating said compressed air by the exhaust gases of the engine, and means for supplying said heated compressed air to the engine piston to assist in the movement in starting the locomotive.

3. A traction unit for internal combustion engine locomotives, comprising a pair of driving axles, each having a plurality of driving cranks, a plurality of opposed combustion cylinders having pistons positively connected to cranks of opposite axles, and means coupling said axles together.

4. A traction unit for internal combustion engine locomotives, comprising a pair of driving axles having inside cranks, oppositely inclined cylinders having pistons positively connected to cranks of opposite axles, and means coupling said axles together.

5. A traction unit for internal combustion engine locomotives, comprising a pair of driving axles, each having a plurality of driving cranks, and a plurality of oppositely inclined cylinders having pistons positively connected to the cranks of opposite axles.

6. A traction unit for internal combustion engine locomotives, comprising a pair of driving axles, each having a plurality of driving cranks, and a plurality of oppositely inclined cylinders having pistons positively connected to the cranks of opposite axles, the opposing groups of cylinders and cranks being in a staggered relation.

7. In an internal combustion engine locomotive, a traction unit comprising a pair of driving axles each having a plurality of inside driving cranks, side frames located out-

- side the driving wheels, and a plurality of oppositely inclined cylinders having pistons positively connected to cranks of opposite axles.
6. 8. In an internal combustion engine locomotive, a traction unit comprising a pair of driving axles each having a plurality of inside driving cranks, side frames located outside the driving wheels, a plurality of oppositely inclined cylinders also located between the side frames and having pistons positively connected to the cranks of opposite axles, and means outside said frames for coupling said axles together.
10. 9. In an internal combustion engine locomotive, a traction unit comprising a pair of driving axles, each having a plurality of inside driving cranks, side frames located outside the driving wheels, a plurality of oppositely inclined cylinders having pistons positively connected to the cranks of opposite axles, cranks at the ends of said axles, and side rods coupling said cranks.
14. 10. In an internal combustion engine locomotive, a traction unit, comprising a pair of driving axles, each having a plurality of cranks, a plurality of oppositely inclined double ended cylinders, each having a piston with a combustion space at one side thereof and a fluid pressure space at the other, piston rods extending through the inner heads of the cylinders, cross heads attached to said rods, and connecting rods from the cross heads to the opposite cranks.
18. 11. In an internal combustion engine locomotive, a traction unit, comprising a pair of driving axles, each having a plurality of cranks, a plurality of oppositely inclined double ended cylinders, each having a piston with a combustion space at one side thereof and a fluid pressure space at the other, piston rods extending through the inner heads of the cylinders, cross heads attached to said rods, connecting rods joining the cross heads of opposite groups of cylinders with the respective opposite cranks, and means for supplying compressed air to the fluid pressure space in said cylinders.
22. 12. In an internal combustion engine locomotive, a traction unit, comprising a pair of driving axles, each having a plurality of cranks, a plurality of oppositely inclined double ended cylinders, each having a piston with a combustion space at one side thereof and a fluid pressure space at the other, piston rods extending through the inner heads of the cylinders, cross heads attached to said rods, connecting rods from the cross heads to the opposite cranks, compressor cylinders with pistons mounted axially on the combustion heads of the engine cylinders, and rods connecting the compressor pistons with the engine pistons.
26. 13. In an internal combustion engine locomotive, a traction unit comprising a pair of driving axles, each having a plurality of cranks, a plurality of oppositely inclined cylinders having pistons positively connected to the cranks of opposite axles, the cylinders being sufficiently inclined to the horizontal to avoid interference between the piston driving connections and the intervening axles.
30. 14. In an internal combustion engine locomotive, a traction unit comprising a pair of driving axles having a plurality of cranks, a plurality of oppositely inclined cylinders and pistons, and positive driving connections from the pistons of said cylinders to the cranks of the opposite axles, the cylinders being sufficiently inclined to the horizontal that the driving connections clear the intervening axles.
34. 15. In an internal combustion engine locomotive, a traction unit comprising a pair of driving axles, each having a plurality of cranks, two sets of oppositely inclined cylinders and pistons, piston rods, cross heads and connecting rods for connecting the pistons of each set of cylinders with the cranks of the opposite axle, the cylinders being sufficiently inclined to avoid interference between said driving connections and the intervening axles.
38. 16. In an internal combustion engine locomotive, a traction unit comprising a plurality of driving axles having cranks, cylinders and pistons located above said axles and having positive driving connections extending from said pistons over an intervening axle to cranks on an adjoining axle, the cylinders being sufficiently inclined to the horizontal to avoid interference between said driving connections and the intervening axles.
42. 17. In an internal combustion locomotive, the combination of a plurality of traction units, each having a plurality of driving axles provided with cranks, internal combustion engine cylinders, and pistons directly connected to said cranks, the units being flexibly connected together, and means for maintaining a fixed relationship between the cranks of all engine-driven axles.
46. 18. In an internal combustion locomotive, the combination of a plurality of traction units, each having a plurality of driving axles provided with cranks, internal combustion engine cylinders, and pistons directly connected to said cranks, means for coupling said driving axles together, flexible means for connecting said units, and a positive mechanical connection between the axles of adjacent units for maintaining a fixed relationship between all of said cranks.
50. 19. In a locomotive, the combination with a direct connected internal combustion engine, of means for storing compressed air,

- mechanism operated by said stored pressure for assisting the internal combustion engine in starting the locomotive, and a second stage air compressor driven by an axle 5 of the locomotive for storing the air at a higher pressure and for reinforcing the air supply.
20. In a locomotive, the combination with a direct connected internal combustion engine, of an air compressor operated during light duty for storing a supply of com-

pressed air, an air motor for assisting the internal combustion engine in starting the locomotive, a second stage air compressor driven during the running of the locomotive for storing the air at a higher pressure, and means for replenishing the air supply from said high pressure storage. 15

In testimony whereof I have hereunto set my hand.

JOHN H. BARNARD.
